(57) **CLAIM**

The ornamental design for a recreational vehicle leveler, as shown and described.

DESCRIPTION

FIG. 1 is a right side view showing my new design;

FIG. 2 is a left side view thereof;

FIG. 3 is a back view thereof;

FIG. 4 is a front view thereof;

FIG. 5 is a top view thereof; and,

FIG. 6 is a perspective view thereof.

In the drawings, the broken lines depict portions of a recreational vehicle leveler that form no part of the claimed design.
